United States Patent Office.

STILLMAN W. ROBINSON AND DE VOLSON WOOD, OF ANN ARBOR,
MICHIGAN.

Letters Patent No. 71,329, dated November 26, 1867.

IMPROVED ROCK-DRILLING MACHINE.

The Schedule referred to in these Letters Patent and making part of the same.

Be it known that we, STILLMAN W. ROBINSON and DE VOLSON WOOD, of Ann Arbor, county of Washtenaw, and State of Michigan, have invented a new and useful Machine for Drilling Rock; and we do hereby declare that the following is a full, clear, and exact description of the construction and operation of the same, so that others skilled in the art may be able to make and use it, reference being had to the annexed drawings, making a part of this specification, in which—

Figure 1 is a perspective view of the machine.

Figure 2 is a longitudinal section through the centre of the cylinder, the piston-rod, and valve.

The nature and main feature of our invention consist in reciprocating the cylinder instead of the piston, and of attaching the drill or drill-holder directly to the cylinder, or a prolongation from it, to cause the drill to reciprocate from and to the rock, and strike it by the direct action of the motor upon the cylinder-heads. The machine may be used as a pounder to strike the drill, thus avoiding the necessity of reciprocating the latter.

The object of this invention is to enable us to make a lighter and stronger machine of less number of pieces and less number of packing-joints than can be done in machines heretofore made; also the cylinder, being plain and without passages, may easily be made of steel, thereby making it more durable, all of which are objects of vital importance in machines of this class.

In the figures, A A are the cylinder, its forward head, and the prolongation to which the drill or drill-holder is attached. These may consist of one or more pieces, as convenience may require. C is the rear cylinder-head, which serves also for rotation, as will hereafter be explained. It is kept screwed into the end of the cylinder by the operation of rotating. B B are the piston and piston-rod, which pass through the hub D, and are secured firmly to it. The motor is admitted to and from the ends of the cylinder through the piston-rod, containing the passages b and c. The valve F, in the chest I, which regulates the admission of the motor to the cylinder, is operated by the tappet C in any convenient manner.

When the motor is admitted to the rear end of the cylinder, and exhausted from the forward end, it presses against the rear head C, and forces the cylinder and all attached back from the rock until the tappet C, acting upon the valve-gear, reverses the valve. The action of the motor is then reversed, and presses upon the forward end of the cylinder, and forces it forward, and causes the drill to strike the rock by the direct action of the motor upon the end of the cylinder.

Rotation is effected by a long click, L, which rotates about one edge as an axis, the other edge of which is spiral, (or, more correctly, helicoidal,) and is pressed against the ratchet C by the spring a. A ratchet, C, is formed on the circumference of the cylinder-head, the teeth of which, during the back stroke, coming in contact with the spiral edge of the click, cause a partial rotation of the head, cylinder, and tool. By this process the cylinder-head is kept screwed into its proper place. During the advance stroke, there being no rotation, the click will fall into the next tooth.

The engine is fed progressively towards the rock in any suitable manner, one method of which we have made the subject of a special application of even date.

What we claim as new, and desire to secure by Letters Patent, is—

In rock-drilling machines in which the drill has a rotary or feed movement, or both, the construction and arrangement of the cylinder so that its prolonged end may serve as a holder for the drill-rod, or for driving the tool, and, at the same time, constitute one of the cylinder-heads to receive the direct action of the motor, which thus produces the operation of drilling rock, &c., in the manner and for the purpose herein described.

Also, the click L, in combination with the ratchet C, (the latter forming the cylinder-head,) in the manner and for the purposes herein described.

STILLMAN W. ROBINSON.
DE VOLSON WOOD.
